Primary Examiner — Sheryl Lane*Assistant Examiner* — Samantha N Wood(74) *Attorney, Agent, or Firm* — Arent Fox LLP(57) **CLAIM**

The ornamental design for a element for a floating waterpark, as shown and described.

DESCRIPTION

FIG. 1 is a perspective view of the element for a floating waterpark showing our new design;

FIG. 2 is a top view thereof;

FIG. 3 is a bottom view thereof;

FIG. 4 is a left side view thereof;

FIG. 5 is a right side view thereof;

FIG. 6 is a front side view thereof; and,

FIG. 7 is a back side view thereof.

The broken lines are included for the purpose of illustrating portions of the element for a floating waterpark and form no part of the claimed design.

1 Claim, 7 Drawing Sheets(56)
